BUCKLE

Carvel Klee, Fort Lee, N. J.

Application May 24, 1950, Serial No. 10,131

Term of patent 3½ years

(Cl. D17—1)

To all whom it may concern:

Be it known that I, Carvel Klee, a citizen of the United States of America, residing in Fort Lee, county of Bergen, and State of New Jersey, have invented a new, original, and ornamental Design for a Buckle, of which the following is a specification, reference being had to the accompanying drawing, forming part thereof, wherein,

I claim:

The ornamental design for a buckle, substantially as shown.

CARVEL KLEE.
